CLAIM

The ornamental design for a backpack for carrying a weighted plate, as shown.

DESCRIPTION

FIG. 1 is a top front perspective view an embodiment of a backpack for carrying a weighted plate showing my new design;

FIG. 2 is a bottom rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top perspective view in an open configuration thereof;

FIG. 10 is a top front perspective view an embodiment of a backpack for carrying a weighted plate showing my new design;

FIG. 11 is a bottom rear perspective view thereof;

FIG. 12 is a front view thereof;

FIG. 13 is a rear view thereof;

FIG. 14 is a left view thereof;

FIG. 15 is a right view thereof;

FIG. 16 is a top view thereof;

FIG. 17 is a bottom view thereof; and,

FIG. 18 is a top perspective view in an open configuration thereof.

The broken lines depict portions of the backpack for carrying a weighted plate that form no part of the claimed design.
